COMBINED HEAT SINK AND HOUSING FOR A SOLID STATE DEVICE

Gerald R. Ritzow, Racine, Rudolph J. Santo, Mequon, and Eugene R. Schmit, Elm Grove, Wis., assignors to Cutler-Hammer, Inc., Milwaukee, Wis., a corporation of Delaware

Filed May 26, 1969, Ser. No. 17,331

Term of patent 14 years

Int. Cl. D13—99

U.S. Cl. D26—1

Fig. 1

Fig. 2

Fig. 3

Fig. 4

FIG. 1 is a top plan view of a combined heat sink and housing for a solid state device showing our new design;

FIG. 2 is a side elevational view of one side thereof, the remaining three sides thereof being identical thereto;

FIG. 3 is a bottom view thereof; and

FIG. 4 is a top plan view of a modified embodiment of the combined heat sink and housing for a solid state device shown in FIG. 1 but drawn to a reduced scale.

We claim:

The ornamental design for a combined heat sink and housing for a solid state device, substantially as shown and described.
